Specification forming part of Design No. 6,964, dated October 21, 1873; application filed September 25, 1873.
[Term of Patent 3½ years.]

To all whom it may concern:

Be it known that we, GEORGE W. LOOMIS and ALFRED T. GOODELL, both of New York, in the county of New York and State of New York, have invented a Design for Sleeve-Button, Pendant, Badge, or Breast-Pin, of which the following is a specification:

The nature of our design is fully represented in the accompanying photographic illustration, to which reference is made.

The plate A is made of oxidized silver, or any other metal or material, and in the shape of a key-stone, on the face of which is a representation, in alto-relievo style, of the Masonic Temple, as erected in the city of Philadelphia, and a representation of the All-Seeing Eye overlooking the temple.

What we claim as our invention is—

A design for a sleeve-button, pendant, badge, or breast-pin, in the shape of a key-stone, and embellished with a view of the Masonic Temple and a figure of the All-Seeing Eye, substantially in the manner above described.
